CLAIM

The ornamental design for a sealable food serving container, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is an exploded perspective view showing a sealable food serving container constructed in accordance with the present invention wherein the lower serving plate and sealing cover are shown separately;

FIG. 2 is a perspective view of the sealable food serving container of FIG. 1 wherein the sealing cover is sealably engaged to the serving plate;

FIG. 3 is a side view in elevation of the sealable food serving container shown in perspective in FIG. 2;

FIG. 4 is a top plan view of the sealable food serving container shown in perspective in FIG. 2 and shown in elevation in FIG. 3; and,

FIG. 5 is a bottom plan view of the sealable food container shown in perspective in FIG. 2, shown in elevation in FIG. 3 and shown in top plan view in FIG. 4.
